UNITED STATES PATENT OFFICE.

SVAN E. JOHNSON, OF RUXTON, MARYLAND.

INTERNAL-COMBUSTION ENGINE.

1,371,686.

Specification of Letters Patent. Patented Mar. 15, 1921.

Application filed July 3, 1920. Serial No. 393,828.

To all whom it may concern:

Be it known that I, SVAN E. JOHNSON, a citizen of the United States, residing at Ruxton, in the county of Baltimore and 5 State of Maryland, have invented certain new and useful Improvements in Internal-Combustion Engines, of which the following is a specification, reference being had to the accompanying drawings.

10 This invention relates to certain improvements in internal combustion engines, and it is an object of the invention to provide a novel and improved device of this general character wherein the intake, compression, 15 firing and exhaust occur during each cycle.

It is also an object of the invention to provide a novel and improved device of this general character comprising a power cylinder and a charging cylinder in communication one with the other and in which are rectilinear movement pistons connected for unitary movement in the same direction, whereby the requisite intake, compression, firing and exhaust occur during each cycle, 25 together with means arranged within the power cylinder to cut off the firing end of said cylinder from the exhaust port during the period such port is open.

The invention consists in the details of 30 construction and in the combination and arrangement of the several parts of my improved internal combustion engine whereby certain important advantages are attained and the device rendered simpler, less expensive and otherwise more convenient and 35 advantageous for use, as will be hereinafter more fully set forth.

The novel features of my invention will 40 hereinafter be definitely claimed.

45 In order that my invention may be the better understood, I will now proceed to describe the same with reference to the accompanying drawings, wherein:

Figure 1 is a fragmentary view partly in 45 section and partly in elevation and of a somewhat diagrammatic character illustrating an engine constructed in accordance with an embodiment of my invention, and

Fig. 2 is a fragmentary transverse sec- 50 tional view taken through the firing end of the power cylinder.

As disclosed in the accompanying drawings, S denotes a shaft provided with a pair of cranks C and C' extending in the same 55 general direction and substantially in parallelism and of substantially the same throw.

Operatively engaged with the crank C is a rod R also operatively engaged with a piston P having rectilinear movement within the power cylinder A. The cylinder A is 60 substantially surrounded by a water jacket J. Positioned adjacent the cylinder A is a charging cylinder B in which is mounted for rectilinear movement the piston P' operatively connected through the instrumentality 65 of the rod R' with the crank C'.

In communication with the firing end of the cylinder A and the adjacent end of the cylinder B is a port 1 and return flow through said port 1 is prevented by the check 70 valve 2 operating in a well known manner. Also in communication with said end portion of the cylinder B is an intake port 3 normally closed by the inwardly opening 75 check valve 4.

In communication with the cylinder A at a desired point inwardly of the port 1 is an exhaust port 5 normally closed by the valve 6. The valve 6 is moved into open position at proper timed sequence by a rock 80 arm 7 engaging the outer end portion of the stem 8 of the valve 6. The requisite rocking movement is imparted to the arm 7 by the rod 9 having an eccentric connection, as 85 at 10', with the shaft S.

As illustrated in Fig. 1, the pistons P and P' have almost reached the limit of their inward movement, the further movement of the piston P within its cylinder B assuring the requisite pressure of the explosive medium within the firing end of the cylinder A and which mixture, under pressure, is delivered within the firing end of the cylinder A through the port 1. Upon ignition of the charge through the medium 95 of a spark plug 10, the pistons P and P' move outwardly in unison and at the same time the valve piston V arranged in the firing end of the cylinder A is moved to a point outwardly of the point of communication be- 100 tween the port 1 and the cylinder A but inwardly of the exhaust 5.

The valve piston V snugly fits within the bore of the cylinder A and is provided in its periphery with the packing rings 11 to 105 prevent passage of the gases. The requisite movement of the valve piston V is effected through the medium of the rock arm 12 operatively engaged with the extended portion of the stem 14 of said valve piston V and 110 which stem extends through the outer head of the piston A. The rock arm 12 has oper-

atively engaged therewith a rod 15 which is also operatively engaged, as indicated at 16, with a cam member 17 carried by the shaft S.

5 As the pistons P and P' move outwardly, the piston P' draws the requisite charge into the cylinder B through the port 3 and as the pistons P and P' move inwardly, the piston P' compresses the charge in the cylinder B and at the same time forces such charge into the firing end of the cylinder A above the valve piston V. The inward movement of the piston P forces the exploded gases out through the exhaust port 5. About the time the piston P on its inward movement reaches the exhaust port 5, the valve 6 closes and the piston valve V is moved to the limit of its inward movement so that the explosive mixture thereabove may pass between the piston P and the valve piston V and which travel of the gases is permitted by the short longitudinal grooves or passageways 18 provided in the wall of the bore of the cylinder A at the firing end thereof, the inner ends of said grooves terminating inwardly of the exhaust port 5 so that when the valve piston V is at the limit of its outward movement, flow through said grooves or passageway 18 is prevented. The pistons P and P' have slight further inward movement resulting in the desired compression of the charge and as the pistons P and P' reach the limit of their inward movement, the spark plug 10 is ignited in a conventional manner.

In order that the spark plug 10 will offer no obstruction to the requisite movement of the valve piston V, I prefer to have the firing portion of said spark plug 10 confined within a groove or passageway 18, as is clearly illustrated in the accompanying drawings.

I also find it of advantage to have the valve piston V hollow and the stem 14 thereof tubular and in communication therewith. By this means, water may be arranged within said valve piston V and the stem 14 to prevent the same from becoming overheated. As is illustrated in Fig. 1 of the drawings, the outer end of the stem 14 has in communication therewith the end portion of a flexible conduit or pipe 19 also in communication with the water jacket J.

From the foregoing description it is thought to be obvious that an internal combustion engine constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise ar-

rangement and formation of the several parts herein shown in carrying out my invention in practice except as hereinafter claimed.

I claim:

1. In an internal combustion engine, a power cylinder, a charging cylinder in communication with the power cylinder, pistons working within the cylinders, means for causing said pistons to move in unison and in the same general direction, an intake port in communication with the charging cylinder inwardly of the piston therein, an exhaust port in communication with the power cylinder outwardly of the communication between said power cylinder and the charging cylinder, and a timed operating piston valve movable within the power cylinder inwardly of the piston within said power cylinder, said piston valve being spaced from the adjacent head of the power cylinder during the period of exhaust. 70 75 80 85

2. In an internal combustion engine, a power cylinder, a charging cylinder in communication with the power cylinder, pistons working within the cylinders, means for causing said pistons to move in unison and in the same general direction, an intake port in communication with the charging cylinder inwardly of the piston therein, an exhaust port in communication with the power cylinder outwardly of the communication between said power cylinder and the charging cylinder, and a timed operating piston valve movable within the power cylinder 90 inwardly of the piston within said power cylinder, said piston valve being spaced from the adjacent head of the power cylinder during the period of exhaust, the wall of the bore of the power cylinder at the 95 firing end thereof being provided with longitudinally disposed channels, said piston valve closing the flow through said channels when at the limit of its outward movement. 100 105

3. In an internal combustion engine, a power cylinder, a charging cylinder in communication with the power cylinder, pistons working within the cylinders, means for causing said pistons to move in unison and in the same general direction, an intake port in communication with the charging cylinder inwardly of the piston therein, an exhaust port in communication with the power cylinder outwardly of the communication between said power cylinder and the charging cylinder, a timed operating piston valve movable within the power cylinder inwardly of the piston within said power cylinder, said piston valve being spaced from the adjacent head of the power cylinder during 110 115 120 125 the period of exhaust, and automatic means for preventing retrograde flow through the communication between the power cylinder and the charging cylinder. 125

4. In an internal combustion engine, a 130

power cylinder, a charging cylinder in communication with the power cylinder, pistons working within the cylinders, means for causing said pistons to move in unison and 5 in the same general direction, an intake port in communication with the charging cylinder inwardly of the piston therein, an exhaust port in communication with the power cylinder outwardly of the communication 10 between said power cylinder and the charging cylinder, a timed operating piston valve movable within the power cylinder inwardly of the piston within said power cylinder, said piston valve being spaced from the adjacent head of the power cylinder during 15 the period of exhaust, automatic means for preventing retrograde flow through the communication between the power cylinder and the charging cylinder, and automatic means for preventing retrograde flow through the 20 intake port of the charging cylinder.

In testimony whereof I hereunto affix my signature.

SVAN E. JOHNSON.
